SCANNING PROCESS

Aloysius J. Cawley, Pittston, Pa.

Application September 10, 1929, Serial No. 391,541
Renewed August 18, 1937

6 Claims. (CL. 178—6.5)

This is a continuation-in-part application of my applications Serial Number 383,390, filed August 3, 1929 and Serial Number 384,687, filed August 9, 1929.

5 The invention relates generally to television, or the transmission of visual images from place to place by means of electromagnetic waves. However, electric currents traversing wired circuits may be used, if desired.

10 More particularly, the invention is concerned with a new scanning means. This term is well known to those skilled in the art, and is the process by which the different portions of the image are brought successively into contact with the photoelectric element at the transmitting station in order that an image variation may be impressed upon the electromagnetic waves that are being transmitted. At the receiving station the scanning apparatus distributes the image-varied 15 light of a neon or other light to the proper portions of the image successively.

Broadly, the scanning means herein described covers the movement in opposite directions of two media each bearing a series of light permeable 20 areas in such manner that there is a continuous intersection of the different members of the light permeable series. These media may be in many different forms.

Two disks are described which are mounted upon different shafts and their margins made to overlap each other, permitting a constant intersection of light permeable areas producing a travelling light dot or point.

A great advantage is that throughout the entire contact area of the two moving media, whether they be disks, tapes, or other, there is a plurality of images formed, and all of these images are in exact synchronism. Means are disclosed showing the manner of projecting several of those 25 synchronous images superposed upon the picture screen, and thus the brightness of the image may be increased to any extent desired by projecting as many images superposed as desired. Thus a great draw back in television is overcome, namely 30 the extreme faintness of the image, which usually permits only silhouettes to be transmitted.

Many special means are shown for moving two disks in opposite directions, including ordinary 35 gear wheels and also worm gearing mechanisms. Those gearings are shown for both separately mounted disks and for concentrically mounted ones.

Some of the many, many variations in the arrangement of the light permeable areas carried

by the two oppositely moving media are illustrated and described.

Special means are shown for projecting the many synchronous images produced by the two moving media are illustrated. These may be 5 projected directly upon the screen or indirectly, by first passing the light beam through a light reflecting means.

Another object of the invention is the use of a third moving medium in the form of a mask, 10 which prevents the passage of light through undesirable portions of the light permeable media.

Still another object of the invention is the formation of several images at the broadcasting station and placing a photoelectric cell in the image 15 field of each image, together with scanning media similar to that described in this specification. This increases the television signal strength many fold.

For a more complete understanding of the invention, reference is to be had to the following description and claims taken in connection with the accompanying drawing, in which like characters of reference denote corresponding parts 20 in all of the views, and in which,

Figure 1 is an elevational view of an arrangement employing the use of ribbons or tapes as moving media carrying light permeable areas. It also illustrates the means for projecting several 25 of the synchronous images superposed upon a screen, and illustrates the use of reflectors for this purpose.

Figure 2 is an elevational view of an arrangement employing a third moving medium in the form of a mask, for the purpose of cutting out the 30 light of undesirable points of intersection of the light permeable areas, and also the viewing of more than one of the synchronous images.

Figure 3a illustrates two media bearing light permeable areas in the form of lines intersecting 35 each other at an angle of ninety degrees. The exact synchronism of the two images is illustrated by means of the arrows. The moving mask is also illustrated.

Figure 3b is an illustration of an apparatus 40 similar to that of Figure 3a, but there are more light permeable areas on the two media.

Figure 3c illustrates two media carrying light permeable areas placed at different angles, and one of those media moving at a speed greatly 45 below that of the other. No mask is necessary with this arrangement.

Figure 1 illustrates a pair of media in the form of two tapes or films which may be modified motion picture films. All throughout the area 50

of contact of the two media A and B, as before stated, there is a series of images produced that are in absolute synchronism. In the case of film media A and B, these would be in a straight line, 5 as shown in Figure 3. They present an elegant opportunity of securing any desired brightness of image. It is simply necessary to project one upon the other upon a screen. This may be done in the disk and cylinder method also, but there 10 is a certain curving of the images, as around the circumference of the disk, while the tapes are in a straight line. However, the method may well be used with the disks or cylinders. Power is applied in any manner desired to shaft 2. 15 Bevel gears 3f, 3e, 3g, 3h cause drums E and D' to move, and they in turn move film B. Worm gearing 4d and 4c cause drums D and E' to move at a speed which is much slower than that of the other two drums. The drums D and E' cause 20 film or tape A to move at a speed that is equal to the number of pictures transmitted per second times the width of a picture. A face view of the films A and B is shown in Figure 3c at the right hand portion. Here it will be noticed that 25 series a, a', etc., are placed a picture width apart and are at right angles to the horizontal. Series b, b', b'', etc., are spaced at such a distance that only one area b will come into relation to area a at any time. The arrows indicate 30 the direction of motion of the dot, or light point formed by the intersection of the scanning lines, which determines the images. It is very important to notice that there is a series of images in synchronism, or in other words, there is a row 35 of images all of which are exactly alike all along the course of the films. This is very important, as they may be projected one upon the other upon a screen. Neon or other lamps 5 are placed one behind each image area and their light shines 40 through and reaches the lens elements 9, which act to project and superpose the images upon the screen 10. This is shown at the lower portion of Figure 1. If it is desired to project images from both the upper and lower portion of 45 the films, a pair of reflectors, such as prisms 19 at both the top and the bottom of the figures project and superpose all images upon 10 at the right. Any degree of illumination is, therefore 50 possible with the apparatus.

50 Figure 2 shows an arrangement wherein the media assume the form of two films moving in opposite directions at a speed which is almost the same. The speed of one is equal to that of the other plus the number of images transmitted per 55 second times the width of a picture. This method necessitates the use of a mask, which is illustrated together with its means of moving it. Power is applied to shaft 2 by any means desired and bevel gears, 3e, 3f, 3g, and 3h cause drums 60 D, E, C and D to move in opposite directions. The gearing is such that B moves faster than A by the above mentioned amount in order that the lines that are drawn or scanned by the intersection i of the two series of light permeable areas 65 may be drawn at successive intervals across the image area. Worm gearing 4d and 4c cause drums C and E' to move film M which carries opaque masking areas as illustrated at the bottom row of frames in Figures 3a and 3b. Here 70 again, neon lamps 5 pass their light through contiguous or adjacent image areas and a series of synchronous images are produced, i. e., a row of images will appear along the tapes, all of which images are alike. Or, this may be better described by saying that there will be a row of ad-

jacent moving pictures moving in exact step all along the tape. This will be made clearer by reading a description of Figures 3a, 3b and 3c below. Mask M moves at a speed equal to the number of pictures transmitted per second multiplied by the width of a picture. It is to be noted that in all of those scanning arrangements that the only difference between the scanning means at the transmitter and receiver is in the employment of photoelectric cells at the transmitter and 5 of neon lamps at the receiver. It is to be noted also that the media at the transmitting station and that at the receiving station move in exact synchronism. However, as the invention is not concerned with the production of a synchronizing 10 apparatus, nor of a radio or broadcasting means, no illustration is given covering either of these. The scanning apparatus disclosed may be used at the receiver or transmitter. 15 Figures 3a, 3b and 3c cover illustrations of the 20 various light permeable areas as employed under different conditions and arrangements. Figure 3a illustrates the two media A and B carrying light-permeable areas a and b. These media move in opposite directions. In this case the fact 25 is brought out that if both media moved in opposite directions at exactly the same speed, we would have a constant passage of a light dot down a portion of the different frames f, f' and f''. In other words, there would be simply the 30 repeated drawing of a line at one point of the frames f, etc. The arrows indicate the direction of the passage of the light dot or of the scanning line. The upper row of the figure at a represents 35 three scanning frames. It will be noted that areas a and b have just met at the upper portion of frame f. In the next row lower down, each area a and b have moved one quarter of a picture width and the arrow indicates that the light i has moved one quarter of the height of 40 the picture. In the third row a and b have moved one-half a picture width and the line has been drawn one half way down the picture, as indicated by the arrow. In the fourth row both a and b have moved three quarters of a picture 45 width, and the line has been drawn three quarters down the picture as indicated by the arrow. In the fourth row a and b have moved a full picture width, and the line is completely drawn as indicated by the arrows. It is to be noted that 50 all during the movement of the two media, there has been a similar and exactly synchronous movement in the frames f' and f'' by other lines, similar to a and b. However, this arrangement would never produce a picture, simply a bright 55 line at some point in each picture frame, f, f', f'', etc. If now either series a or b is given a speed that is greater than that of its companion by an amount equal to the number of pictures transmitted per second multiplied by the width 60 of the picture, the repeated scanning lines will not be drawn in the same position as indicated by the arrows, but each successive line will be drawn in a slightly different position, and since the whole image field will be successively covered by the scanning lines, we will have an image 65 produced. By thus increasing the speed of a, the lines will be successively drawn to the left, and by increasing the speed of b they will be drawn to the right. Here again, another defect is introduced which must be remedied if a perfect 70 image is to be transmitted. As the lines shift their position to the left or right, at certain times, other light points, which are shown in the illustration as being coincident with, or covered by 75

the frame margins, will be brought into the picture area. Thus there would be two or more light intersecting points in the image field, and the image would be improperly produced. To make this clearer, let us suppose that the apparatus is operated very slowly and that you can actually see the lines *b* that are back of medium *A*. If the apparatus were run slowly, the design represented by the slant lines (somewhat resembling that of wall paper) would appear to move from the top to the bottom of the picture, i. e., coming from the top and disappearing at the bottom. Now, when *a* or *b* is given an excess of motion, in addition to the movement just mentioned, this design will also shift to the right or left. The five views at Figure 3a illustrate this readily. If the two media run at equal speeds, we would have seven lines scanned or drawn, three indicated by the three arrows and four indicated by the margin of the frames, since when there is no lateral movement, the course of the intersecting lines is clearly indicated. A third medium, as described in connection with Figure 2, is introduced, which carries a series of opaque areas, and this is called the mask *M*. This is shown in the lower row of the figure. It acts to hide or mask the undesirable light dots *i* produced by undesirable intersections of lines *a* and *b*. This medium is given a speed equal to the number of pictures per second multiplied by the width of a picture. The masking medium may be in the form of disks, tapes, cylinders, or the like, according to which system is used. It is evident that the excess speed of *a* or *b* over that of its companion is the same as the speed of the mask *M*. With the employment of the mask, as described, we will have the production of real and perfect images. The frames *f*, *f'* and *f''* are supposed to have neon lamps back of them. The frames may be shifted to the right or to the left in order to bring the picture into proper frame, as desired. By supplying a large number of frames, as many pictures as desired may be obtained, and they will be in exact synchronism if the frames are properly adjusted in their left to right position. Those images may be superposed upon a screen by projection, and thus it is possible to have any degree of brightness of the image desired. Figure 3b shows an arrangement similar to that at *a* with the distinction that there are twice as many lines or light permeable areas *a* and *b* per picture width than in the former. The opaque portions of the mask *M* in the lowest portion of the figure are modified in order to cut out the increased number of undesirable intersections.

Figure 3c shows an entirely different arrangement than the two illustrated at Figures 3a and 3b. Here the two media move at greatly unequal speeds. One, such as *A* and consequently *a*, is moved at a speed equal to the number of pictures per second multiplied by a picture width. This speed is very slow, and this particular disk may be used as the guide to synchronism of the picture as the other medium is closely attached to it from a speed standpoint, due to the gearing connecting both. The other medium is moved at a great speed. The faster it is rotated, the more lines are drawn per second, and if the slow moving medium is kept at the rate of motion corresponding to fifteen pictures per second, then we have a greater number of lines per picture, which means more detail. If the speed of *B* is increased four-fold while that of *A* remains constant, we have four times

the definition in the image. *a*, *a'*, *a''*, etc., act as rules along which *b*, *b'*, *b''*, etc., draw repeated lines while *a*, etc., are slowly shifted. It is also to be noted that increase of speed, meaning more lines per second, also increases the brightness. The flexibility of the system is indicated by the fact that if you speed up *B* and do not maintain that of *A* at the same low rate, you will get an increased number of pictures per second, each having the same former number of lines. This is similar to the old spiral hole disk. The increase of the number of lines per picture, however, is a great advantage, as it increases detail or half-tone effect in the picture. At the present time it is barely possible to transmit silhouettes. In the old spiral disk method, each succeeding hole was placed at a lower point in the frame, i. e., it scanned the picture frame at a lower portion than its predecessor. Consequently, two pictures taken, or "framed", at different points on the disk would be out of synchronism. Also the number of lines per picture was limited by the number of holes that could be placed around the periphery of the disk, and the number of holes was further limited by the fact that they had to be a picture width apart. In the twin disk method described herein, there is no difference between one light permeable line *a* and its next neighbor. The number of scanning lines, per picture, therefore, is not limited by the size of the disk or other medium. In the spiral hole disk there is a limit to the size of the picture than can be scanned or transmitted. Experts seem agreed that three feet is the largest practical disk that can be conveniently, or practically rotated. The largest sized picture that can be transmitted or scanned by a three foot disk is two inches. This is due to the fact that at least forty eight holes placed a picture width (or two inches) apart will use all of the available space on the periphery of the disk. In the twin disk method, the only limit to the size of the picture is really the distortion produced by the curvature of the disks, the pictures tending to assume the form of partial segments of a circle, and also they are not placed in a straight line but traverse the circumference of the circle. Those defects are, however, easily remedied by substituting tapes for the disks, as described in this and the previously identified applications. Then there is perfect symmetry. By employing a small picture frame, say one inch wide, on a three foot disk, there would be fifteen four-hundred-and-fifty line pictures produced per second. If the disk had two light permeable lines per picture width, as shown at Figure 3b and Figure 3c, there would be fifteen nine-hundred-line pictures per second. This would give as much detail as that possessed by a motion picture. Then by projecting several images superposed on a screen, any degree of image brightness desired could be obtained. Of course, tapes may be used as media *A* and *B*, and indeed, motion picture films photographed in such manner that the light permeable areas are mere transparencies may be used.

At the transmitting station, a plurality of images may be produced of the objects to be transmitted. Thus Figure 1 may be taken as a representation of the transmitter. The screen 10' or 10 may be then taken to represent the objects to be transmitted. Several images are formed by lens or optical elements 9. Each image has a photoelectric cell in its area. The scanning devices *A* and *B* distribute the light points synchronously through the various image areas, and con-

sequently, photoelectric cells 5 are all actuated in synchronism to vary the electric current in synchronism with the images. This factor lends a high degree of intensity to the signals, i. e., the 5 image-varied electromagnetic waves that are being broadcasted. The principle of image duplication thus described is available at the transmitter as well as at the receiver, and this means powerful, distinct television broadcasting.

10 Again referring to Figure 3c, in the top row *b*4 has partly intersected with *a*, as indicated by the arrow. In the second row it has traversed three-quarters of the course of *a*, and in the third row it has completed it, and *b* has commenced to 15 traverse *a*; one line has been drawn or scanned and another is being drawn immediately next to it. In the fourth row the arrow indicates that *b* has traversed almost the entire length of *a*. In the fifth row, *b*' has started to traverse *a*, 20 and *b* has finished its passage over *a*. Thus, two lines have been drawn, and a third has been started. It will be noticed that *a* has been shifting its course gradually throughout, while *b* has moved an entire picture width. *a*, however, 25 shifts its position uniformly and steadily and does not stop still while *b*, etc., traverse it, and then move on. Consequently, there will be a slight deviation of the lines from the vertical. However, this will be so slight that it will not be 30 noticed. As the scanned lines are shifting their position successively, there will be a visual image. There will also be a series of pictures, one in each frame, and they will be in exact synchronism. As lines *b*, etc., are so arranged that but 35 one of them traverses line *a* at a time, and since *a*, etc., are spaced a picture width apart, there can be but one light point *i* in any frame at a time. Consequently, no mask is necessary with this arrangement. It also employs but two media. The 40 pictures or images, since they are in synchronism may be superposedly projected upon a screen or viewed by the eye directly, and thus any degree of brightness may be obtained by this superposition.

45 The frames *f*, *f'*, *f''* (as many as desired) are movable laterally, and thus the picture may be brought into frame by this movement. The frame at the receiving station must be placed at a position corresponding to that at the transmitting station with regard to media A and B, 50 and photoelectric elements 5, whether they be photoelectric cells, or neon or other lamps. This framing process can be thus utilized also in bringing the picture into focus, i. e., "into frame". 55 For instance, A and B at the transmitting and receiving stations may be moving at exactly synchronous speeds, but the light point in the frame at the transmitter may be located at a different point in the frame than the light point in the receiver frame is located. Lateral shifting of the 60 frame may be utilized to remedy this. The contiguous frames *f*, *f'*, *f''*, *f'''*, etc., as many as desired, may be made in one piece since the synchronizing of one image brings about the synchronization of all with the image at the transmitting station.

Having described my invention, I claim as new and desire to procure by Letters Patent:

1. A scanning apparatus consisting of a plurality of optical image forming means, a plurality of photoelectric cells coacting with each of said optical means, a plurality of differentially moving media bearing intersecting light permeable areas acting to produce a plurality of light transmitting openings which traverses the elemental areas of said images synchronously, said light permeable areas on each of said media being rectangular and parallel, and means for moving said media, said photoelectric cells acting to synchronously vary the intensity of an electric current in accordance with said images. 15

2. The process of scanning which consists in forming a plurality of similar images, synchronously and successively converting the elemental areas of said images into an image varied current corresponding to said images. 20

3. A scanning apparatus which consists of two differentially moving scanning elements each bearing a series of parallel, rectangular light permeable areas, said light permeable areas coacting to form by their intersections a plurality of light transmitting points, each of said points acting to traverse the elemental areas of adjacent sections of said elements, a plurality of optical elements forming similar images in each of said sections and a plurality of photoelectric cells one in each of said images and being acted upon by said light transmitting points to produce an intense image-varied current. 30

4. A scanning apparatus consisting of two scanning media and means for differentially moving said media, a plurality of adjacent image areas, each of said media bearing a series of parallel rectangular light-transmitting areas which by their intersections form a plurality of light transmitting openings which synchronously traverse the elemental areas of a plurality of image-varied light sources, a plurality of optical image forming means coacting with said light sources to produce a composite image composed of a plurality of superposed similar images. 45

5. A scanning apparatus consisting of two endless tapes bearing light permeable areas, means for moving said tapes, one of said tapes embracing the other in the same plane, said tapes bearing each a series of parallel rectangular light permeable areas, a plurality of adjacent image areas, a plurality of photoelectric elements supplied with a common current on one side of said tapes and a plurality of optical elements on the opposite side of said tapes, a reflector associated with said optical elements and a screen associated with said reflector. 50

6. A scanning process which comprises forming several images of an object, simultaneously scanning the same points on said images, producing separate photoelectric currents by said 60 scanings and combining said currents to produce a single current.
